A. J. Gibson

Running Gear.

bolt to A. J. Patented May 27, 1856.

Hold spring
in place.Additional Improvement
to Pat. No. 11,668.spring
seat.Fig. 1

The Hiro ended coupling on
permits rocking motion of
front and rear axles.

The threaded connection
is the same as
front axle
coupling.

No. 144 to original Letter Patent No. 11,668 - Improved Coupling for

What I claim is, in combination, above the threaded bolt and with respect
to the guard, a seat or connection for the spring or other part of a carriage, as described, a seat or connec-

I also claim an arrangement of the threaded bolt and so as to pass up
through it and its seat or connection for the reception of a screw
head, serving not only to hold the bolt in its seat or connection, but
for the specific purpose of preventing accident in case of breakage
of the bolt or nut, as described.
